DOOR LATCH

George W. Slopa, Chicago, Ill.

Application December 29, 1947, Serial No. 794,366

5 Claims. (Cl. 292—123)

1

This invention relates generally to door hardware and more specifically to a refrigerator door latch.

Doors of the type used on refrigerating or cold storage cabinets installed in food dispensing establishments are generally subjected to severe use in service. Particularly the locking and latching means mounted on the door and cabinet are subjected to such severe use and, consequently, must be substantially and durably constructed. It has been found, however, that even though the locking and latching means heretofore used were constructed of ample proportions, the spring means usually employed therewith failed after a relatively short period of service to properly actuate the locking member to effect a positive closure and locking of the door, thereby resulting in a high loss of efficiency of the refrigerating cabinet.

Accordingly, it is an object of my invention to provide latching and locking means of the type described, which means is operative to effect a positive closure of the door of a refrigerator cabinet even under severe service conditions.

A further object of this invention is the provision of locking and latching means of the type described which is simple and durable in construction and highly efficient in operation.

Other and further objects of the present invention will be apparent from the following description and claims, and are illustrated in the accompanying drawings which, by way of illustration, show an exemplary embodiment and the principles thereof. Other embodiments of the invention embodying the same principles may be used, and structural changes may be made as desired by those skilled in the art, without departing from the present invention and the purview of the appended claims.

In the drawings:

Fig. 1 is a plan view of latching and locking means embodying my invention with certain parts cut away and others in broken lines to show details of construction, the latching means being shown in locking position.

Fig. 2 is a similar view showing the latching and locking means in unlocked position.

Referring to the drawings wherein is shown a preferred embodiment of my invention, the numeral 15 designates generally a latching device comprising a housing member 6 provided with a pair of spaced perforated ears 7, the housing being mounted, as with screws 9, on the forward face of a refrigerator door 8, the door being of the overlapping type.

A drawbar 11, provided with a cylindrical por-

tion 12 and with a portion 13 substantially rectangular in cross section, is arranged to slide in said housing through an aperture provided at one end thereof. A slot 14 is provided in the drawbar 11 to accommodate the tongue 16 of an actuating lever handle 17 pivotally mounted between the ears 7. A compression spring 18 embraces the cylindrical portion 12 and abuts the shoulder 19 provided in the housing 6 and the end of the portion 13, the spring 18 normally urging the drawbar 11 to the left, as viewed in Figs. 1 and 2. The terminal end 21 of the drawbar 11 is bifurcated to provide spaced ears which are perforated, and which accommodate the end of a latch member 22, which is pivotally connected thereto as by a pin 23.

The latch member 22 is pivotally secured to the perforated ears 24 of a member 26 which is mounted on the edge of the door 8, the said latch member being provided with a retaining notch 27 engageable with a keeper mounted on the door frame 29. Both the retaining notch 27 and keeper 28 are provided with cam surfaces 30 and 31 respectively, which coact when the door is being closed to cause the latch member 22 to swing in a counterclockwise direction so as to permit engagement of the notch 27 with the keeper 28.

The portion of the latch member 22 located substantially medially between the pivot point 32 and the retaining notch 27 is formed with spaced ears or extensions 33—33 between which is accommodated a tension spring 34. The said spring is secured to the latch member 22 through the medium of a bolt 36 having a perforated head. The other end of spring 34 is similarly secured to an extension 37 on the base of the member 26. Tension on the spring 34 may be adjusted by manipulation of the lock nuts 38 associated with the bolt 36. The ears 33—33 serve to conceal the spring 34 to prevent injury to one operating the latching device and serve also as stops to limit pivotal movement of the latch 22 in a clockwise direction when the edges 39 of the ears 33 abut the extension 37 of the member 26.

It will be noted that the cooperating surfaces of the retaining notch 27 and the keeper 28 are provided with inclined cam faces 41 and 42 respectively, so arranged that when the door is in closed position they securely retain the door against the frame 29.

It is thought that the operation of this latching device will be clearly understood from the foregoing, but, briefly stated, it is as follows:

In normally closed position the parts are in the relation shown in Fig. 1. To open the door

the lever handle 17 is grasped and pulled away from the face of the door. The tongue 16 associated with the handle engages against an end wall of the slot 14 in the drawbar 11 and causes the drawbar to move to the right. This action causes the latch member 22 to pivot in a counter-clockwise direction and effects disengagement of the retaining notch 27 from the keeper 28, as shown in Fig. 2. Upon release of the handle 17 the spring 18 acts to return the handle to normal position and the spring 34 acts on the latch member to return it to normal locking position, as shown in Fig. 1. It will be understood that the springs 18 and 34 complement each other in their functions, the spring 34 acting at all times to effect a positive closure of the door regardless of the condition of the spring 18. However, should either of the springs fail in service, closure of the door 8 would still be effected by the remaining spring until the broken spring could be replaced.

It is to be understood that the form of my invention, herewith shown and described, is to be taken as a preferred example of the same, and that various changes in the shape, size and arrangement of parts may be resorted to without departing from the spirit of my invention, or the scope of the appended claims.

I claim:

1. Latching means for retaining a door in closed position against the door frame, including a supporting member mounted on a face of the door adjacent an edge thereof, a drawbar slidably mounted on said supporting member and projecting beyond said door edge, a member mounted on the edge of said door substantially adjacent said supporting member, a latch member pivotally supported between its ends on said last recited member and operatively connected at one end to one end of said drawbar, said latch member having a retaining notch at its other end adapted for engagement with a keeper carried on the door frame, spring means associated with said drawbar for urging the same in a direction to effect engagement of said retaining notch with said keeper, and separate spring means associated with said latch member and acting on the same at a point between the pivotal axis thereof and said retaining notch and normally urging said notch into engagement with said keeper.

2. Latching means for retaining a door in closed position against the door frame, including a supporting member mounted on a face of the door adjacent an edge thereof, a drawbar slidably mounted on said supporting member and projecting beyond said door edge, a member mounted on the edge of said door substantially adjacent said supporting member, a latch member pivotally supported between its ends on said last recited member and operatively connected at one end to one end of said drawbar, said latch member having a retaining notch at its other end adapted for engagement with a keeper carried on the door frame, spring means associated with said drawbar for urging the same in a direction to effect engagement of said retaining notch with said keeper, and a separate spring connected to said door edge and to said latch member at a point between the pivotal axis thereof and said retaining notch and normally urging said retaining notch into engagement with said keeper.

3. Latching means for retaining a door in closed position against the door frame, includ-

ing a supporting member mounted on a face of the door adjacent an edge thereof, a drawbar slidably mounted on said supporting member and projecting beyond said door edge, a member mounted on the edge of said door substantially adjacent said supporting member, a latch member pivotally supported on said last recited member and operatively connected at one end to one end of said drawbar, said latch member having a retaining notch at its other end adapted for engagement with a keeper carried on the door frame and having a hollow portion substantially intermediate the pivotal axis thereof and said retaining notch, spring means associated with said drawbar for urging the same in a direction to effect engagement of said retaining notch with said keeper, separate spring means associated with said latch member and substantially concealed in said hollow portion and normally urging the retaining notch of said latch into engagement with said keeper, and means for disengaging said retaining notch from said keeper.

4. Latching means for retaining a door in closed position against the door frame, including a supporting member mounted on a face of the door adjacent an edge thereof, a drawbar slidably mounted on said supporting member and projecting beyond said door edge, a member mounted on the edge of said door substantially adjacent said supporting member, a latch member pivotally supported on said last recited member and operatively connected at one end to one end of said drawbar, said latch member having a retaining notch at its other end adapted for engagement with a keeper carried on the door frame and having top and bottom portions projecting beyond the vertical inner edges thereof to form a housing located substantially intermediate the pivotal axis and the retaining notch of said latch, and spring means directly associated with said latch member and substantially concealed in said housing and normally urging said retaining latch into cooperative engagement with said keeper.

5. Latching means for retaining a door in closed position against the door frame, including a supporting member mounted on a face of the door adjacent an edge thereof, a drawbar slidably mounted on said supporting member and projecting beyond said door edge, a member mounted on the edge of said door substantially adjacent said supporting member, a latch member pivotally supported on said last recited member and operatively connected at one end to one end of said drawbar, said latch member having a retaining notch at its other end adapted for engagement with a keeper carried on the door frame and having a housing portion substantially intermediate the pivotal axis and the retaining notch of said latch, and spring means associated with said latch member and substantially concealed in said housing portion and normally urging the retaining notch into engagement with said keeper.
